ILLUMINATING DEVICE

Henry W. Trost, Rochester, N. Y., assignor to
Bausch & Lomb Optical Company, Rochester,
N. Y., a corporation of New York

Application July 18, 1946, Serial No. 684,601

1 Claim. (Cl. 40—132)

1

The present invention relates to a surface illuminator and more particularly to a device for illuminating eye testing charts or the like.

It is an object of the present invention to provide a novel device of the above type which is light, compact, and easily constructed by economical manufacturing processes.

It is a further object to provide such a device wherein diffused light rays are reflected indirectly with equal intensity and with overlapping coverage upon a display panel from opposite sides, the overlapping rays complementing each other to produce a uniform and glareless illumination.

It is a further object to provide such a device in the form of a two-section cabinet, one section of which is removable, whereby the inner parts such as the lamp, transformer, mirrors, and other apparatus are exposed and may be easily serviced.

Further objects and advantages will be apparent to those skilled in the art by reference to the following description and accompanying drawing in which:

Fig. 1 is a perspective view of a preferred embodiment of the invention.

Fig. 2 is a sectional view on an enlarged scale taken on the line 2—2 of Fig. 1, and

Fig. 3 is a fragmentary side elevation of the cabinet in disassembled position, showing the locking mechanism for joining the sections of the cabinet.

In Fig. 1 of the drawing, a cabinet of any desired form generally indicated at 11 is shown comprising a rear or base section 12 and a demountable section 13. In the preferred form of the invention here shown, the rear or base section 12 is constructed with a rear wall 14 extending the full height of the cabinet, the wall 14 being flanked by the angularly disposed walls 15 and 16 which in turn join the side walls 17 and 18. A partial top wall 19 is attached to the side walls 15, 16, 17, and 18 and rear wall 14, and a floor 20 is provided in the cabinet having the full depth of the assembled cabinet. The front and sides of the cabinet floor 20 are surrounded by a low wall 21 which joins the side walls 15, 16 to form a bottom compartment 22.

The demountable front section 13 of cabinet 11 is a self-rigid structure embodying a front wall 23 flanked by the angularly-disposed walls 24 and 25 which in turn join the side walls 26 and 27 forming a shape symmetrical with the rear section 12. An aperture 28 is formed in the front wall 13 covering a major part of the front

2 wall area. A bottom wall 29 and a top wall 30 are joined to the contiguous side walls 24, 25, 26, 27 and front wall 23, and are vertically spaced so that the top walls 19 and 30 of the rear and front sections, respectively, are in substantial alignment when the bottom wall 29 nearly rests on the upper edge of the base wall 21. Means for attaching the demountable section 13 to the base section 12 are provided in any suitable manner such as a pin-and-slot connection as best shown in Fig. 3 in which the pins 31 are fixed to the front section of the cabinet and the inclined slots 32 are formed in the edge of the rear section. The weight of the front section 13, 15 hanging on the pins 31 when engaged in the inclined slots 32, assures that the sections 12 and 13 remain assembled regardless of vibration or accidental shock.

A display panel for eye testing charts or the like is provided in the form of a rigid opaque wall 33 mounted mutually parallel to the front wall 23 and back wall 14 in a position to substantially prevent light from within the cabinet from traveling directly forward through the aperture 28. The panel 33 is secured at the top and bottom to the walls 30 and 29, respectively of the front section 13, and the width of the panel is less than the width of the cabinet 11 sufficiently to form vertical elongated passages 34 and 35 along opposite sides thereof.

Means for slidably receiving and retaining a sheet 36 of cardboard or other suitable material against the display panel 33 is provided in the form of slotted guideways 37 and 38 extending 35 along the vertical edges of the panel 33 to accommodate the sheet. Characters 39 may be placed on the sheets 36 in any desired pattern such as those found suitable for eye testing charts. A slot 40, cut through the top wall 30 40 in alignment with the front surface of the display wall 33, permits the sheets 36 to be inserted into the guideways 37 and 38 from the top thereof without opening the cabinet. Lips 41 and 42 are provided at the mouth of the slot 45 40 to assist in inserting the sheets 36.

According to the present invention, means are provided for uniformly and indirectly illuminating a display panel with diffused light rays, said means comprising an elongated diffused source 50 of light such as a fluorescent lamp 43 and a front and a rear pair of reflectors or mirrors. The fluorescent lamp 43 extends substantially the full height of the cabinet 11 and is spaced equally from the side walls 17 and 18 throughout its length. Means are provided for supporting the

lamp 43 on the vertical center line of the back wall 14 in the form of brackets 44 fixed at the top and bottom, respectively, to the back wall 14. Lamp 43 is energized through a lead 45 by any suitable means such as a transformer 46 fixed to the floor 29 of the compartment 22 and connected to a suitable source of power, not shown, and any preferred switch arrangement may be used to control the lamp. Light shields 47, 48, 49, 50, fixed to the vertical edges of wall 33 so as to 10 extend substantially crosswise of said edges from top to bottom, are provided to control the direction of the diffuse light rays which are projected upon the sheet 36. It has been determined by research that the brightness of a luminous 15 tube light source is greatest in a centrally-disposed zone between its ends. In the present device, means are provided for equalizing the vertical distribution of light on the chart 36 to substantially compensate for the longitudinal variation in the brightness of the lamp 43. Such means are in the form of suitable modifications in the profile shape of the light shields 47 and 48 which extend vertically substantially parallel to the lamp 43. By providing protruding portions such as 50' of any desired shape, the light rays which are projected toward the mirrors 51 and 52 may be cut off to control the amount of light 20 reflected thereby.

The rear pair of reflectors or mirrors 51 and 52 are held in a fixed position by any suitable means such as brackets 53 across the angularly-disposed walls 15 and 16 of the base section 12. Mirrors 51 and 52 are coextensive in length with the lamp 43 and are set at such an angle with reference thereto that a maximum amount of the light from the lamp is reflected forwardly through the vertical apertures 34 and 35 onto the mirrors 54 and 55 in the front section 13. The front pair of mirrors 54 and 55 are fixedly 40 mounted by any suitable means such as brackets 56 across the angularly-disposed walls 24 and 25 and extend vertically to the same height as the rear mirrors. Mirrors 54 and 55 are spaced in the cabinet section 13 so as to receive the light rays passing forwardly through the apertures 34 and 35. In order to provide an indirect uniform illumination on the sheet 36, the front mirrors 54 and 55 are set at such an angle with reference to the front wall 23 that the diffused light rays from these mirrors cross and overlap so that the near rays 56 which are reflected from one front mirror are augmented by the far rays 57 which are reflected from the other front mirror. It has been found by extensive experimentation that the approximate angle at which the mirrors 54 and 55 may be set to accomplish this result is 28° to the front wall 23. By this method, the additive effect of the diffuse light rays from 45 mirrors 54 and 55 incident on every point of the

illuminated surface is substantially the same, thus providing a uniform shadowless illumination thereon.

Although but one form of the invention has been shown and described in detail, it will be understood that other forms are possible and that changes may be made in the proportion, shape, and arrangement of the parts without departing from the spirit of the invention as defined in the appended claim.

I claim:

An eye-testing device comprising a cabinet having a base section and a demountable section, said base section having a rear wall and said demountable section having a front wall and an aperture therein, means for attaching the demountable section to the base section, an elongated fluorescent lamp extending substantially across and attached to the rear wall substantially along the vertical center line thereof, an opaque display wall fixed in said demountable section parallel to said front wall and having substantially the same length as said lamp, said display wall extending entirely across said aperture and spaced rearwardly therefrom, an eye chart mounted on said display wall, and means for uniformly illuminating said eye chart with diffused light rays, said means including flat mirrors in optical alignment with said lamp and angularly fixed in said cabinet for reflecting the light rays from said lamp onto the front surface of said chart with equal intensity, the angle of said mirrors being chosen so as to provide overlapping complementary light rays from opposite sides; and light shields extending along the vertical borders of said display panel for controlling the direction of the light rays which impinge on said chart, said light shields having means thereon for equalizing the vertical distribution of light rays from said lamp upon said chart to substantially compensate for longitudinal variations in the brightness of said lamp.
